UNITED STATES PATENT OFFICE.

GEORGE A. HOFFMAN, OF MANSFIELD, OHIO.

GASEOUS-FUEL BURNER.

1,405,214.

Specification of Letters Patent. Patented Jan. 31, 1922.

Application filed April 2, 1921. Serial No. 458,145.

To all whom it may concern:

Be it known that I, GEORGE A. HOFFMAN, a citizen of the United States, residing at Mansfield, in the county of Richland and State of Ohio, have invented certain new and useful Improvements in Gaseous-Fuel Burners; and I do declare the following to be a full, clear, and exact description of the invention, such as will enable others skilled in the art to which it appertains to make and use the same.

My invention relates to improvements to gaseous fuel burners for numerous uses and has more particular reference to burners of the type provided with a plurality of closely associated slits through which the fuel discharges. The principal object of my invention is to provide an improved and greatly simplified construction, whereby the necessary slits may be formed by spacing a plurality of metal strips apart wherever a flame is required, and securing said strips tightly together at the ends of the slits. In addition to manufacturing advantage, a burner constructed in this manner will produce a much hotter blue-green flame since it provides for thorough mixing of the gaseous fuel with air and more thorough combustion.

A further object of the invention is to provide a burner head of novel construction for receiving and holding the structure above referred to.

With the foregoing in view, the invention resides in the novel construction and association of parts hereinafter described and claimed, the descriptive matter being supplemented by the accompanying drawings.

Figure 1 is a side elevation of a burner constructed in accordance with the invention.

Figure 2 is a top plan view, the several slits, however, being shown in diagram only.

Figure 3 is an end elevation.

Figure 4 is a central vertical longitudinal sectional view as indicated by line 4—4 of Figure 2.

Figure 5 is a horizontal sectional view as designated by line 5—5 of Figure 4.

Figure 6 is a vertical transverse sectional view as indicated by line 6—6 of Fig. 4.

Figure 7 is a perspective view of a portion of the burner head and the bent metal strips which are held thereby.

In the drawings above briefly described, I have illustrated my invention in connection

with a straight burner intended primarily for use in a gas heater, but it will be understood that the novel features of construction herein disclosed may be employed in numerous other relations.

The numeral 1 designates a plurality of pairs of metal strips which are secured together at longitudinally spaced intervals as indicated at 2, electric welding being preferably employed for this purpose although it is not essential. Between the points 2, the strips 1 are bulged outwardly as indicated at 3, the extent of the bulge increasing gradually from the center of the series of strips to the outermost of these strips. By thus bulging the strips, a plurality of fuel discharge slits 4 are provided and I have here shown these slits disposed in truly parallel relation, although this is not absolutely essential.

While any preferred form of burner head may be employed for holding the strips 1 and supplying gaseous fuel to slits 4, I prefer to construct this head in the manner shown. Its body portion 5 is formed of a single sheet of metal bent into substantially the form of a tube with its free edge portions 6 disposed in approximately parallel relation and bent alternately outwardly and inwardly as designated at 7 and 8 respectively, whereby to snugly receive the bent strips 1, which strips may be secured between the walls or edge portions 6 by welding or in any other suitable way. A pair of preferably flanged end plates 9 close the ends of the body 5 and may well carry brackets 10 by means of which the entire burner is supported, although it will of course be understood that other supporting means could be used if desired.

Discharging into the lower side of the burner head or body 5, I have shown a suitable type of gas and air mixer 11 which is preferably provided with one valve 12 to be set according to the gas pressure and with another valve 13 for turning the gas off and on as required. To prevent the fuel from the mixer 11, escaping only through the intermediate slits 4 of the series without flowing to the ends of the burner head and discharging equally through the several slits, I mount a longitudinal partition 14 in the burner head. The edges of this partition are provided with downturned flanges 15 electrically welded or otherwise secured to

the sides of the burner head. The ends of said partition are notched as indicated at 16, and its intermediate portion is perforated at 17. The notches 16 and the perforations 17 permit the proper escape of fuel into the upper portion of the burner head so that it will be equally discharged through the several sets of slits 4, thereby producing jets of equal height throughout the length of the burner. Furthermore, the partition is of advantage as a reinforcing means for the sheet metal head 5.

By employing the construction shown and described or an equivalent construction, not only is a burner provided which may be easily and inexpensively manufactured, but actual tests have shown that by providing the slits 4, much more intimate mixing of the gas and air takes place as it is burned, giving an extremely hot blue-green flame.

While the details disclosed are adequate in connection with the form of burner indicated, it is to be understood that the improved features may be embodied in connection with burners of other shapes and for other purposes, without affecting the scope of the invention as claimed.

I claim:

1. A burner comprising a plurality of pairs of metal strips contacting with and secured against each other at longitudinally spaced points, but bulged outwardly and separated from each other between said points to provide a plurality of fuel outlet slits or holes, and a burner head carrying said strips, said slits being in communication with said head.
2. A burner comprising a plurality of pairs of metal strips contacting with and secured against each other at longitudinally spaced points, but bulged outwardly and separated from each other between said points

to provide a plurality of fuel outlet slits or holes, and a burner head having spaced walls between which said strips are held, said walls having outwardly bulged portions receiving the outwardly bulged portions of said strips. 45

3. A burner comprising a plurality of pairs of metal strips contacting with and secured against each other at longitudinally spaced points, but bulged outwardly and separated from each other between said points to provide a plurality of fuel outlet slits or holes, a sheet of metal bent into approximately tubular shape with its edge portions disposed in substantially parallel relation and receiving said strips therebetween, said edge portions being outwardly bulged to receive the outwardly bulged portions of said strips, and end plates forming with said sheet of metal a burner head. 55 60

4. A burner comprising a plurality of pairs of metal strips contacting with and secured against each other at longitudinally spaced points, but bulged outwardly and separated from each other between said points to provide a plurality of fuel outlet slits or holes, a sheet of metal bent into approximately tubular shape with its edge portions disposed in substantially parallel relation and receiving said strips therebetween, said edge portions being outwardly bulged to receive the outwardly bulged portions of said strips, end plates forming with said sheet of metal a burner head, and a perforated partition secured longitudinally in said burner head between its fuel inlet and said outlet slits. 70 75

In testimony whereof I have hereunto set my hand.

GEORGE A. HOFFMAN.
